UNITED STATES PATENT OFFICE

JOHN H. BURKHOLDER, OF ASHLAND, OHIO, ASSIGNOR, BY MESNE ASSIGNMENTS, TO
ELITE MANUFACTURING COMPANY, A CORPORATION OF OHIO

VEHICLE JACK

Application filed September 20, 1928. Serial No. 307,095.

The present invention relates to vehicle jacks, and more particularly to an improvement in wheeled jacks in which ratchet means and an oscillatory lever are used to 5 raise and lower a vehicle or other load. The present jack structure is relatively low in height so that it may be readily wheeled underneath the body of an automobile. In that position the handle may be oscillated 10 and the operating means easily controlled at a remote distance from the lifting parts either to raise or lower the load. In general the object of the invention is to provide a jack of that type with improved means and 15 devices for effectively controlling and safeguarding the raising and lowering operations, all as hereinafter explained in greater detail.

In the accompanying drawings, Fig. 1 is a 20 top view of the jack, showing a portion of the operating handle broken away, and Fig. 2 is a side view thereof. Fig. 3 is a sectional view horizontally through the lifting members and a portion of the frame. Fig. 4 is 25 an enlarged sectional view vertically through the central part of the jack. Fig. 5 is a reduced view, of the jack, largely diagrammatic, to illustrate a lifting operation. Fig. 6 is a side elevation and sectional view of 30 the jack with portions thereof broken away in places to more clearly disclose the controlling devices. Figs. 7 and 8 are diagrammatic views illustrating different ratcheting operations which occur at successive intervals in lowering a load. Fig. 9 is a trans- 35 verse vertical section, on line 9—9 of Fig. 6, and Fig. 10 is a similar view on line 10—10 of Fig. 6. Figs. 11 and 12 are perspective views of the two pawls which co-act with 40 the segmental ratchet teeth in raising and lowering the load. Fig. 13 is a perspective view of the slideable controlling member for 45 the operating pawls. Fig. 14 is a perspective view of the gravity dog which is used to support an extensible rack upon the main lift member.

Structurally considered the jack consists of a skeleton frame made of two vertical side members 2—2 rigidly connected in parallel spaced relation by two axles 3—3 and three

cross shafts, or bolts, 4, 5, and 6, respectively. Wheels 7 upon axles 3—3 support the frame movably upon a floor, and a relatively long tubular handle or lever 8 permits the jack to be shifted to and fro with ease and convenience. Handle or lever 8 is also the main operating member for the jack, being pivotally connected to cross bolt 4 at one end of the frame. The pivotal connecting parts for the lever consist of two triangular pieces 9—9 which are bolted at their longer ends to the opposite sides of one end of the lever and suspended from cross shaft 4 at their upper corresponding angular corners, thus permitting the lever to be oscillated in a vertical plane. The lower angular corners of triangular pieces 9—9 carry a crank pin 10, to the projecting ends of which a yoke member 11 is attached. The triangular pieces operate in effect as crank members; whereby a powerful thrust movement may be imparted through yoke 11 to a short connecting pin 12 and a pawl 13 pivotally supported thereon. The pawl and pin swing in an arc, being suspended from higher cross shaft 5 by a pair 70 of links 14—14. Pawl 13 is confined between said links opposite a series of ratchet teeth 16 on a circular segment 17 mounted in a rotatable position upon cross shaft 5. An integral arm 18 extends forwardly from segment 75 17, and a parallel arm or link 19 is hinged at one end to the upper shaft or bolt 6 in the jack frame. The free ends of arms 18 and 19, respectively, are pivotally connected to a hollow standard 20 carrying a rack bar 21. A lift member 22 is pinned at its top to the upper end of rack bar 21, and the load is engaged and lifted either by the head 23 or a step 23' on member 22 when pawl 13 80 engages the ratchet 16 and rotates segment 17 on its axis. However, before operating the jack mechanism, the lift member 22 may be elevated independently by hand to a near engaging position with the load and locked or held thereat by a spring-pressed dog 24 85 which is pivoted on the connecting pin 25 for the upper parallel arm or link 19. Rack bar 21 is slideably confined within hollow standard 20, and lift member 22 is of U-shape 90 in cross section to embrace and slideably en-

gage three of the outer sides of the standard. The rack bar and lift member may also be lowered in respect to the standard by disengaging dog 24 from the rack teeth by hand or automatically. For that purpose dog 24 is provided at its upper end with a lateral finger 26 which may be engaged by hand, and at its lower end or below its axis with a depending part having a side lug 27 adapted to be engaged at certain intervals in the operation of the jack by a reciprocable controlling member in the form of a slidable bar 28, see Fig. 6. In addition, bar 28 serves to control the working positions of the main actuating pawl 13 and a holding pawl 29, the latter pawl being pivotally mounted upon the cross shaft or bolt 4 centrally between the triangular cranking sections or pieces 9-9 for the handle or lever 8. In oscillating the handle or lever to either raise or lower the load the two pawls 13 and 29 engage different ratchet teeth 16 alternately to support the load. However the respective movements of the two pawls differ in raising and lowering operations. Thus in raising a load step by step, both pawls may be held in constant working contact with ratchet teeth 16 by separate coiled springs 30 and 31, respectively, whereas in lowering the load, step by step, it is necessary to retire the holding pawl and hold it inactive for an interval against the tension of its spring to permit each tooth to pass the pawl in an upward direction step by step. In lowering a load with the present jack a more powerful spring 32 is attached to reciprocable bar 28 to counter-check at certain intervals the weaker springs for pawls 13 and 29, and also the individual spring for dog 24. For that purpose bar 28 is slidably supported and provided with several projecting portions adapted to come into contact at timed intervals with both pawls and the dog. There are three such contact portions on the bar; first, a lateral finger —a— at its upper rear end immediately adjacent a vertical projection —a'— on holding pawl 29; second, an angular branch —b— depending from the lower part of the bar above pawl 13 and behind a vertical projection *b'* on the pawl above its pivot; and third, a slanting nose or extension —c— at the front end of the bar directly opposite the side lug 27 on dog 24 below its pivot.

Reciprocable bar 28 is slotted longitudinally at its rear end to receive and rest upon an inwardly-projecting hub 33 on one of the triangular pieces 9, see Figs. 6 and 10, while the front end of the bar is provided with a shouldered supporting finger 34 which extends laterally through a horizontal slot 35 in the adjacent side member 2 of the jack frame, see Figs. 2 and 3. The outer end of finger 34 is provided with a washer 36 or other means to hold bar 28 in slidable connection with side member 2, and the counterchecking

spring 32 is attached at one end to a lug 37 at the inner side of the same side member 2 and at its opposite end to a side lug 38 on bar 28, see Fig. 3. Spring 32 tends to pull bar 28 constantly forward, and this tension of the spring is utilized at times to lock and hold the bar out of action or in an inactive position upon drawing bar 28 rearwardly by a rod 39 which may be locked in a fixed position by its bent extremity 40. Thus, rod 39 is hooked pivotally to one end of bar 28 and extends rearwardly therefrom along the top of handle 8 to a keeper 41 riveted or otherwise affixed to the handle. The bent extremity 40 is projected to one side of handle 8 and rests in a sliding position upon a longitudinal rib 42 on keeper 41 until the rod is pulled and the angular extremity 40 is free to drop or to be pressed down behind the vertical end edge 43 of rib 42 where locking is effected.

Assuming the rod to be locked as described the jack may be used to raise a load. In that operation the first movement of the handle or operating lever is upward, thus rotating it on pivot bolt 4 and causing the suspensory links for pawl 13 to swing and carry the pawl upwardly in an arc over the ratchet teeth 16 but only a distance sufficient to clear one tooth. In the meantime holding pawl 29 is engaging a tooth on segment 17 to support the load. Also finger —a— on bar 28 is in a re-tired position so as not to prevent free rocking of pawl 29 on its pivot under the action of its coiled spring 31. Accordingly, when a reverse or downward movement of lever 8 takes place active pawl 13 engages a tooth and segment 17 is rotated in a direction which raises lift member 22, and the ratchet tooth engaged by the holding pawl moves in the same direction until this pawl clears another tooth and is caused by its spring to engage it and relieve active pawl 13 of the load. Lever 8 may then be moved upward again and the same operations repeated any number of times within the working limits of the jack. A lowering operation involves a different setting of reciprocable bar 28 and rod 39, therefore the first proceeding is to unlock rod 39 from keeper 41, thereby permitting bar 28 to be drawn forward by spring 32 so that the action of active pawl 13, holding pawl 29, and dog 24, may be automatically controlled.

For example, it is assumed that lift member 22 is in an elevated position carrying a heavy weight or load with lever 8 in a substantially horizontal position at the beginning of the lowering operation, and that the active pawl 13 and the holding pawl 29 are each engaged with separate teeth on rotatable segment 17. The operator may then lower the load by depressing lever 8 slightly, which movement forces active pawl 13 forward and rotates segment 17 correspondingly against the weight of the load. The rotative movement of segment 17 unlocks holding pawl 29 from the

ratchet tooth with which it has been engaged, and the strong spring 32 pulls bar 28 forward and presses finger —*a*— on the bar against the vertical projection —*a'*— on holding pawl 29, thereby overcoming weaker spring 31 and tilting the pawl apart from the ratchet tooth. During this proceeding the operator supports the load by lever 8, and the holding pawl will remain in the released position while the manual pressure on the lever is relieved to permit the lever to swing upwardly and lower the load one step. Pawl 13 is locked to the ratchet tooth by the weight of the load while it moves rearwardly, thus permitting the vertical projection *b* on pawl 13 to engage and press the depending branch *b* on bar 28 rearwardly a corresponding distance, thereby carrying finger —*a*— away from projection *a'* on the holding pawl and permitting the weaker spring 31 for this pawl to swing the pawl toward and into engagement with a ratchet tooth. Pawl 29 now holds ratchet member 17 from further rotation and the load is supported thereby at a lower elevation than formerly while lever 8 is inclined upwardly with pawl 13 still engaged with a ratchet tooth. To release pawl 13 and complete the cycle of movements necessary to position the parts for another lowering movement the handle or lever 8 is lifted or raised slightly above the point where it rests normally after the load comes to a state of rest. Thus pawl 13 is pulled rearwardly when the lever is lifted, while holding pawl 29 prevents ratchet member 17 from moving in the same direction. Spring 32 then pulls bar 28 forward and the depending branch *b* on the bar presses against the vertical lug *b'* on pawl 13 and tilts the pawl downwardly out of engagement with the ratchet teeth. The weight of lever 8 now causes it to drop and carry pawl 13 forwardly opposite another ratchet tooth on rotatable member 17. Bar 28 follows this movement but is brought to a stop by hub 33 thereby permitting projection *b'* to move apart from depending part *b* on the bar, whereupon the weaker controlling spring 30 swings the pawl upwardly behind a ratchet tooth on rotatable member 17. The working parts are now in the same position as at the beginning to produce a second lowering operation, that is, a further lowering movement may be produced by repeating the steps described.

Upon completing lowering operations and bringing the load to a rest position upon some other support than the jack, it is of advantage to collapse or telescope the extensible member 22 within hollow standard 20. This result is effected automatically by bar 28 after the jack has been relieved of its load. Thus, when bar 28 is drawn forward to its limit by spring 32 the nose or extension *c* at the front end of the bar engages or is engaged by the side lug 27 on dog 24, thereby tilting the dog

out of contact with the teeth on rack bar 21. Thereupon, lift member 22 drops by gravity to a place of rest upon hollow standard 20. However, lift member 22 will not drop when a load is supported thereon, inasmuch as the pulling power of spring 32 on bar 28 is not sufficient in itself to unlock and release the dog from the rack bar while these parts are subjected to a heavy pressure from above.

What I claim, is:

1. A vehicle jack, including a frame, a ratchet member rotatably supported upon said frame, a lift member operatively connected with said ratchet member, a holding pawl for said ratchet member, an active pawl suspended to swing in respect to said ratchet member, an oscillatory lever connected with said active pawl, a longitudinally movable bar slidably mounted upon said frame and positively engageable with each of said pawls, and a spring for controlling the longitudinal movement of said bar in one direction, said active pawl being engageable with said bar to move it in an opposite direction during the lowering movement of said lift member.

2. A vehicle jack, including a frame, a rotatable segment having ratchet teeth rotatably supported upon said frame, a lift member linked to said segment, and a holding pawl and an operating pawl engageable with said teeth, springs controlling the movement of said pawls, a longitudinally movable bar slidably mounted upon said frame, having projecting portions to positively engage said pawls, a spring to control the movement of said bar and an oscillatory lever connected with said operating pawl.

3. A vehicle jack, including a frame, a rotatable segment supported upon said frame having ratchet teeth and a rigid arm, a lift member connected to said arm, a link parallel to said arm connecting said lift member to said frame, a holding pawl and an operating pawl and springs to press said pawls in engagement with said ratchet member, a reciprocable bar having projections positively engageable with said pawls, a spring connected with said bar adapted to release said pawls from said ratchet member, and an oscillatory lever linked to said operating pawl.

4. A vehicle jack, including a frame, a ratchet member rotatably supported upon said frame, a lift member operatively connected with said ratchet member, a holding pawl pivotally supported on said frame, an operating pawl suspended to swing opposite said ratchet member and pivotal support of said holding pawl, each of said pawls having a projecting portion and a controlling spring, a longitudinally movable bar slidably mounted upon said frame having projecting parts positively engageable with the projecting portions on said pawls, a spring for slidably shifting said bar in said frame to effect a re-

lease movement of each pawl, and an oscillatory lever linked to the operating pawl.

5. A vehicle jack, comprising a frame mounted upon wheels, a rotatable ratchet member supported upon said frame, a load supporting member connected to said ratchet member, a holding pawl pivotally supported upon said frame, an operating pawl suspended to swing from said frame, an oscillatory lever connected with said frame having link connection with said operating pawl, each of said pawls having a projecting portion and a controlling spring, a reciprocable bar slidably supported upon said frame having a controlling spring, projecting portions on said bar positively engageable with the projections on said pawls, and means for locking said bar in an inactive position.

6. A vehicle jack, comprising a frame, a rotatable ratchet member mounted upon said frame, a load supporting member connected with said ratchet member, a spring-pressed holding pawl for said ratchet member an operating pawl suspended to swing from said frame, a slideable operating bar longitudinally shiftable within said frame having contact engaging relation with each of said pawls, a spring shifting the bar in one direction, a rod and means for shifting and holding said bar in an opposite direction, an oscillatory lever having a link connection with said operating pawl.

7. A vehicle jack, including a frame, a rotatable ratchet member mounted upon said frame, a load supporting member connected with said ratchet member and vertically adjustable in respect thereto, holding and operating pawls for rotating said ratchet member, a holding device for said adjustable load supporting member, an oscillatory lever mounted upon said frame and connected with said operating pawl, and a single release member engageable with said pawls and said holding device.

45 8. A vehicle jack, including a frame, a rotatable ratchet member mounted upon said frame, an adjustable and collapsible load supporting member connected with said ratchet member, holding and operating pawls for said ratchet member, an operating lever mounted upon said frame and connected with said operating pawl and a reciprocable bar slidably mounted upon said frame, said bar including a series of projecting portions co-operating with said pawls and actuating said adjustable load supporting member to automatically collapse said jack and its adjustable load supporting member when free from the weight of the load.

55 9. A vehicle jack, including a frame, a ratchet member mounted upon said frame, a load supporting rack bar connected with said ratchet member, a pivotal dog on said ratchet member engageable with said rack bar, a holding pawl and an operating pawl

for said ratchet member, an oscillatory lever connected with said operating pawl, a reciprocable bar having portions engageable with said holding and operating pawls and also said dog during lowering movements of the 70 load supporting member, and means to shift said bar into engagement with said pawls and dog to disengage said dog from said load supporting rack bar whereby the rack bar is caused to drop when the load is moved 75 from the supporting member.

10. A vehicle jack, including a frame, a ratchet segment rotatably mounted upon said frame having a rigid arm, means for rotating said segment step by step, a lift member 80 pivotally connected to said arm and to a link hinged to said frame and parallel to said arm, a load supporting rack bar telescoped within said lift member, a pivoted dog engageable with said rack bar, and a spring-pressed bar movably supported upon said frame having an extension engageable with said dog when said arm of said ratchet segment is in its lowest position for automatic release of said dog when said lift member is lowered.

11. A vehicle jack, including a frame, a rotatable ratchet segment supported upon said frame, a lift member connected with said segment, a rack bar telescoped within said lift member, a pivoted dog engageable with said rack bar, a holding pawl and an operating pawl for said ratchet segment, an oscillatory lever connected with said operating pawl, a reciprocable bar supported upon said frame having contacting portions for each pawl and also said dog, a spring connected with said bar, and means connected with said lever and the bar for holding said bar in an inactive position.

105 12. A vehicle jack, comprising a wheeled frame, a circular segment rotatably mounted upon said frame having ratchet teeth and a rigid arm, a vertical lift member hinged at its lower end to said arm, a link hinged to said frame and the upper part of said lift member, a rack bar telescoped within said lift member, a pivoted dog engaged with said rack bar having a depending projection, a pivoted holding pawl for said ratchet segment having a projecting lug, an operating pawl and means to suspend the same from said frame in a swinging position opposite said ratchet segment, said operating pawl having a projection thereon, springs pressing each pawl into contact with said ratchet segment, an oscillatory lever connected with said frame having a crank connection with the swinging suspensory means for said operating pawl, a slideable bar having contact portions engageable with the projections on said pawls, said bar extending into contact position where it may be engaged by the depending projection on said dog during lowering movements of said lift member, a spring to

draw said slideable bar forward, and means for pulling said slideable bar rearwardly and for locking it in that position.

13. A vehicle jack, comprising a frame, a rotatable ratchet member upon said frame, a load supporting member connected with said ratchet member, a spring actuated holding pawl for said ratchet member pivotally supported upon said frame, a spring actuated operating pawl for said ratchet member suspended from said frame to swing around said ratchet member, a longitudinally shiftable bar slidably mounted upon said frame, having projections to effect positive contact with said pawls, a spring to control the longitudinal movement of said bar in effecting a release of said operating pawl from said ratchet member, swinging links pivotally connected with said frame, to suspend said operating pawl, an oscillatory lever pivotally mounted upon said frame having link connection with said swinging links, a rod connected with said bar extending lengthwise of said lever, and means on said lever for locking said rod to said lever.

25 In testimony whereof I affix my signature.
JOHN H. BURKHOLDER.
